ELECTRONIC DEVICE FOR SOUND REPRODUCTION OF MUSICAL INSTRUMENTS

Frank T. Cooper, Santa Cruz, Bombay, India

Application December 10, 1948, Serial No. 64,686
In India January 28, 1948

3 Claims. (Cl. 84—1.14)

1

This invention relates to musical instruments, and more particularly to an electronic pickup device for use with musical instruments of the stringed type, such as pianos, guitars, and the like.

A main object of the invention is to provide a novel and improved pickup device for use with a stringed musical instrument to enhance the tone of the instrument, increase its volume range and to enable a player to obtain many unusual tone effects normally not available with the instrument.

A further object of the invention is to provide an improved pickup device for use with a stringed instrument in conjunction with an electronic amplifier, said pickup device being very simple in construction, compact in size, so that it is easy to install where space is restricted, and which is very durable, so that its sensitivity remains substantially constant over long periods of time, and regardless of whether or not the instrument is used during said time periods.

Further objects and advantages of the invention will become apparent from the following description and claims, and from the accompanying drawings, wherein:

Figure 1 is a front elevational view, partly broken away, of a conventional piano equipped with an electronic sound pickup device constructed in accordance with and installed in accordance with the present invention.

Figure 2 is an enlarged cross-sectional detail view taken on line 2—2 of Figure 1, showing one method of installation of the pickup device.

Figure 3 is a view similar to Figure 2 but illustrating the method of installation of the pickup device employed with a piano differing somewhat in construction from the piano of Figures 1 and 2.

Figure 4 is an enlarged longitudinal vertical cross-sectional view taken on line 4—4 of Figure 2, showing the internal structural details of one sectional unit of the pickup device.

Figure 5 is a top plan view, partly broken away, of the pickup device sectional unit shown in Figure 4.

Figure 6 is an exploded side elevational view of the core portion of the pickup device sectional unit of Figures 4 and 5, showing the various components of said core portion.

Figure 7 is a schematic wiring diagram showing the manner in which the pickup device is connected to an electronic amplifier.

Referring to the drawings, and more particularly to Figures 1 and 2, 11 designates a conven-

2

tional piano provided with the usual arrangement of strings 12 and provided with an action including the hammers 13 and the dampers 14 arranged above the hammers. In accordance with the present invention a wooden support bar 15 is secured to the frame members 16 of the piano, said support bar 15 being closely adjacent to and transverse to the strings 12. Secured to the support bar 15 by means of bolts 17, 17 in each of the respective string sections defined by the spaced frame members 16 is a pickup element 18, said pickup element extending parallel to the support bar 15, being held closely adjacent the strings 12, and being substantially coextensive with the length of the associated string section.

As shown in Figure 3, if the piano action is of a design wherein the dampers, shown at 14' are located below the hammers, shown at 13', 20 the support bar 15 is fastened to the piano frame above the hammers and the pickup elements 18 are suspended from the bar 15 by means of the bolts 17. In the design shown in Figures 1 and 2, the support bar 15 is fastened to the piano frame inwardly adjacent and below the hammers, and the pickup elements 18 are supported above bar 15 by means of said bolts, as shown in detail in Figure 4.

As shown in Figures 4 to 6, each pickup element 18 comprises a pair of parallel spaced flat iron bars 19 and 20 between which are secured a plurality of spaced permanent magnets 21, said magnets having their north poles in contact with bar 19 and their south poles in contact with bar 20. The bolts 17 pass through the end portions of the end magnets 21, as shown in Figure 4. Shorter bolts 27 are employed to secure the magnets to the bars inwardly of the end bolts 17.

40 The magnets 21 are polarized longitudinally as well as vertically and are positioned with longitudinal ends of like polarity adjacent each other as shown in Figure 6, wherein "N" and "S" designate the vertical poles of the magnets and "E" and "W" designate the longitudinal poles of the magnets. The outer ends of the end magnets are of like polarity, for example, both being "east" poles, as indicated in Figure 6. The respective bolts 17 and 27 are of non-magnetic material, such as brass.

By the arrangement above described, the permanency of the composite magnet core is better assured, inasmuch as, if the magnets 21 were mounted with their "E" and "W" poles adjacent 55 each other there would be a tendency for the mag-

nets to dissipate their longitudinal magnetic forces through one another and through the adjacent bridging portions of the pole bars 19 and 20. Also by this arrangement the flux density in the air space between the marginal portions of the pole bars 19 and 20 is increased. As shown in Figures 5 and 6, the bars 19 and 20 project substantially beyond the side planes of the magnets 21 and also project beyond the end planes of the magnets at the ends of the pickup element, 10 whereby the composite core is defined. Wound on this core is a coil 22 which is confined within the space between the bars 19 and 20.

Since the iron bar 19 is in contact with all the north pole faces of the magnets 21, bar 19 becomes the north pole of the composite magnet defined by the above described assembly, and similarly, bar 20 becomes the south pole thereof. The magnetic flux threads through the turns of the coil 22, and any fluctuation of said flux induces a corresponding voltage in said coil. 15

As shown in Figure 4, the pickup elements 18 are supported on the support bar 15 by the elongated end bolts 17, said bolts being provided with suitable nuts 23 for holding the pickup elements in parallel spaced relation to the support bar. The pickup elements 18 are therefore held with the longitudinal edges of their pole bars 19 and 20 closely adjacent to and transverse to the piano strings 12, with the magnetic flux between the pole bars threading around the piano strings with substantial density. Vibration of a string therefore produces a corresponding vibratory fluctuation of the magnetic flux, which induces a corresponding fluctuating voltage in the associated 25 coil 22.

The coils 22 may consist of any desired number of turns, but preferably consist of a small number of turns of heavy wire to increase the ruggedness of the unit. As shown in Figure 7, 40 the respective coils 22 of the pickup elements are connected in series, and the resultant series pickup circuit is connected to the low-impedance primary of an output transformer 24 whose secondary is of high impedance and is connected to the input terminals of a conventional electronic amplifier 25. The amplifier output is connected to a pair of line wires 26, 26 across which one or more loud speakers may be connected. Amplifier 25 may be mounted within the piano or may be external thereto, and is provided with suitable gain control means to regulate the degree of amplification thereof.

Since each string 12 of the piano acts to produce a flux variation when vibrated, the strings act as individual voltage generators with respect to the coils 22 and the resulting voltages are amplified in a desired degree by the amplifier 25. Of course, the string struck can only affect a section of the coil 22 adjacent thereto but that is sufficient to generate a sufficient signal voltage in the entire coil to feed the amplifier. Other strings struck will affect different parts of the coil 22 and spread through the coil. For example, assume that a chord facing a single coil is struck. Several operative voltages are generated in this single coil but these several voltages are of different frequencies and they will be reproduced consequently as a chord through the amplifier, the volume of sound being greater than that produced by a single note. The amplifier setting is, however, kept at a level where, when the maximum number of strings which can possibly be struck are thus struck, there will be no audible distortion. The greater volume of 55

sound resulting when a chord is struck, as against that resulting from a single note is not at all out of proportion to the natural increased sound emanating from a normal piano when a chord is struck. The normal sound output of the piano is therefore augmented by the output of the electronic tone generating system above described, with a resultant increase in volume and a modification of tone quality which may be regulated by suitable adjustment of amplifier 25. By the use of suitable output filter devices in the amplifier, well known per se, the sound output of the system may be regulated so as to produce a predominance of either bass, treble, or intermediate tones, whereby numerous interesting tonal effects may be obtained.

In view of the thin elongated shape of the pickup elements 18, said elements may be readily mounted in a restricted space and therefore 20 can be installed in practically all designs of pianos without modification of the pianos. While disclosed specifically herein as being employed with pianos, the device may be installed on any stringed instrument employing strings having magnetic permeability, such as on steel guitars, and the like.

The magnets 21 are preferably of the high-density type, such as Alnico, or the like, having high stability. Since a plurality of magnets 21 30 are employed in each pickup element, deterioration of one of the magnets will not substantially impair the sensitivity of the pickup element, and the pickup device will remain operative over long periods of time.

While a specific embodiment of an electronic sound reproducing device for stringed musical instruments has been disclosed in the foregoing description, it will be understood that various modifications within the spirit of the invention may occur to those skilled in the art. Therefore it is intended that no limitations be placed on the invention except as defined by the scope of the appended claims.

What is claimed is:

45 1. In combination with a stringed instrument, a pickup element mounted transverse to the strings of the instrument and adjacent to said strings, said element comprising a pair of parallel elongated flat bars of magnetically permeable material having opposing longitudinal margins, a plurality of permanent magnets secured between the bars at longitudinally spaced intervals with their north pole faces in contact with one of the bars and their south pole faces in contact with the other bar, said magnets being arranged with adjacent longitudinal ends of like polarity, and a coil wound on and surrounding the magnets and extending longitudinally between the bars with its turns positioned in the spaces between the respective opposing longitudinal margins and the ends of the bars.

50 2. In combination with a piano, a pickup element mounted on the piano frame transverse to the strings of the piano and closely adjacent to said strings, said element comprising a pair of parallel flat elongated iron bars having opposing longitudinal margins, a plurality of permanent magnets disposed between the bars at longitudinally spaced intervals and having adjacent longitudinal ends of like polarity, the magnets having their north pole faces in contact with one of the bars and their south pole faces in contact with the other bar, transverse fasteners securing said magnets between the bars, the longitudinal margins of the bars extending substan-

tially beyond the side faces of the magnets, and a coil wound on and surrounding the magnets and extending longitudinally between the bars with its turns positioned in the spaces between the respective opposing longitudinal margins of the bars, the planes of the bars being substantially normal to the plane of the piano strings, whereby a substantial density of magnetic flux is present around the piano strings.

3. In combination with a piano, electronic 10 pick-up means mounted on the piano and including a plurality of pick-up elements disposed transversely to the strings of the piano and adjacent thereto, said pick-up elements being longitudinally spaced and wired in series with an 15 amplifier, each of said elements comprising a pair of parallel flat iron bars having opposing longitudinal margins, a plurality of permanent magnets secured between the bars at longitudinally spaced intervals with their north pole faces in 20 contact with one of the bars and their south pole faces in contact with the other bar, the longitudinal margins of the bars extending substantially

beyond the side faces of the magnets, and a coil wound on and encompassing the magnets and extending longitudinally between the respective opposing longitudinal margins of the bars, the planes of the bars being substantially at right angles to the plane of the piano strings, whereby substantial density of magnetic flux is present around the piano strings.
